UNITED STATES PATENT OFFICE.

CHARLES P. STEINMETZ, OF SCHENECTADY, NEW YORK, ASSIGNOR TO
GENERAL ELECTRIC COMPANY, OF NEW YORK.

ELECTRIC-ARC LAMP.

SPECIFICATION forming part of Letters Patent No. 678,058, dated July 9, 1901.

Application filed April 8, 1901. Serial No. 54,869. (No model.)

To all whom it may concern:

Be it known that I, CHARLES P. STEINMETZ, a citizen of the United States, residing at Schenectady, county of Schenectady, State of New York, have invented certain new and useful Improvements in Electric-Arc Lamps, (Case No. 1,479,) of which the following is a specification.

One of the objects of my present invention 10 has been to produce an arc-lamp in which the arc-regulating mechanism is caused to respond promptly and vigorously to any change or tendency to change of current passing through the arc. This sensitiveness of the 15 arc-regulating mechanism enables me to dispense either wholly or almost entirely with external resistance or other devices for securing stability of operation of the lamp. The means whereby I secure this result may 20 briefly be described as comprising a plurality of coils acting upon the regulating mechanism of the lamp, one of these coils—as, for example, that one which serves to separate the carbons—being opposed by another one of 25 the coils, the resulting action upon the mechanism being therefore due to a differential effect. The coil which serves to separate the carbons I will term for convenience the “main” coil, and in this coil I cause current 30 to vary at a rate different from the rate of variation of current in the other coil, which for convenience I will term the “differential” coil. The effect of a fluctuation of current in the arc is to cause the resultant action 35 of the regulating-coils upon the arc-controlling mechanism to vary at a greater rate than the rate of variation of current in the arc, thereby temporarily magnifying and rendering more vigorous the action of the arc-regulating mechanism.

In the drawings, Figure 1 represents in diagram one embodiment of my invention, and Fig. 2 a modified form of the same.

Referring to Fig. 1, the part numbered 45 1 represents the core of a pair of solenoids 2, this core being operatively connected in any ordinary manner—as, for example, through the clutch 3—with the carbon or other electrode 4. The coöperating carbon or electrode 50 5 is indicated at 5. The solenoids 2, with which the core 1 coöperates, are provided

with two windings, one of which is connected so as to act in opposition to the other. The main winding 6 is proportioned so as to have a greater effect than the opposing winding 7, the differential effect of the two windings together being such as to maintain the desired separation of the electrodes 4 and 5.

The main winding 6 is so arranged that upon the occurrence of a variation of current in the arc there will be a larger proportionate, although temporary, change of current in the said main winding. The differential winding 7 is arranged so that the current therein varies either at the same rate as the variation of current in the arc or at a slower rate, as may be desired. The connections whereby these results are secured may differ considerably without departing from the spirit of my invention. One of the means 60 for accomplishing the result is, however, shown in Fig. 1, and consists in dividing the main circuit as it enters the lamp at 8 into two branches, one of which (indicated at 9) passes through the main coil 6, and the other branch 65 (indicated at 10) passes through an inductance or kicking coil 11, then through the reversely-wound or differential coil 7, and joins the other branch 9 at some point, as 12, from which the circuit continues through the carbons 4 5 and out to the other terminal of the lamp, (indicated at 13.)

The branch 9, including the main coil 6, is proportioned so as to have a higher resistance than the branch 10, the latter branch, on the other hand, being caused, principally by the use of the inductance-coil 11, to have a higher self-induction than the first-mentioned branch. Any means other than that described for securing a difference between the 80 time constants of these two branch circuits is of course well within my invention.

Suppose, for example, a sudden increase of current occurs in the arc due perhaps to a sudden wasting away of particles of carbon. Then 85 owing to the difference in time constants of the two branch circuits 9 and 10 the current through the main coil 6 will increase at a higher rate than that through the arc, while that in the differential coil 7 will increase 90 slower. While these changes are going on the pull exerted by the differential action of the

solenoids 2 upon the core 1 will be temporarily increased in an almost impulsive manner, the pull on the core rising rapidly at first and then declining as the current reaches a steady 5 value. A decrease of current through the arc of course has an exactly opposite effect, the sustaining force of the solenoids being temporarily decreased in a proportion considerably greater than the decrease of current 10 in the arc, thereby allowing a rapid readjustment of the electrodes by driving the current back to its normal value.

Fig. 2, which represents the modified form 15 of my invention, differs from Fig. 1 only in that the differential coil 7 instead of being connected in series with the inductance-coil 11 is connected directly in series with the main line 8. This connection, while in some respects not as advantageous as that shown 20 in Fig. 1, is, however, nevertheless highly useful and constitutes one of the embodiments which my invention may assume.

The mode of operation will be readily understood from the explanation above given, 25 it being only necessary to add that the effect of the differential coil 7 instead of varying slower than the variation of the current in the arc, and thereby enhancing to a corresponding extent the regulating effect of the 30 main coil 6, varies, on the other hand, at the same rate as the variation of current in the arc, since, as shown, it is in series therewith.

As various modifications may be made in the embodiment of my invention without departing from the spirit thereof, I do not desire 35 to be limited to the particular details shown.

What I claim as new, and desire to secure by Letters Patent of the United States, is—

1. In an electric-arc lamp, the combination 40 of differentially-acting coils connected so as to respond with different degrees of promptness to variation of current in the arc, and arc-regulating mechanism operatively related to said coils.

2. In an electric-arc lamp, the combination 45 of branch circuits of different time constants, coils connected respectively in said branch circuits, and arc-regulating mechanism operatively related to said coils.

3. In an electric-arc lamp the combination 50 of arc-regulating mechanism operated on by differentially-acting coils, and branch circuits of different time constants into which said coils are respectively connected.

4. In an electric-arc lamp, the combination 55 of branch circuits of different time constants, said branch circuits including a main coil or winding in one of said branches and a differential coil in another branch, and arc-regulating mechanism operatively related to said coils.

5. In an electric-arc lamp, the combination 60 of branch circuits a main coil or winding in one of said branches, a differential coil and an inductance-coil in another branch circuit, and arc-regulating mechanism operatively related to said coils.

In witness whereof I have hereunto set my hand this 5th day of April, 1901.

CHARLES P. STEINMETZ.
